UNITED STATES PATENT OFFICE

EDWARD W. HALL, OF PORTLAND, OREGON

PROPELLION MECHANISM

Application filed August 11, 1930. Serial No. 474,421.

My present invention relates to an improved propulsion mechanism for water craft, the mechanism being of the endless chain type with blades or paddles operating 5 along the keel line of a flat bottom boat. The propulsion mechanism, while adapted for various types of boats, is especially designed for use with motor boats, pleasure craft, or speed boats, of light draft, and the arrangement of the propulsion mechanism 10 permits navigation of the boat in comparatively shallow water, as well as in deeper waters.

The propulsion mechanism is designed to 15 provide a high speed drive for the boat, with impulses that render the drive practically continuous, and with a smoothness that eliminates substantially all vibrations of the boat. Means are also provided for cushioning, or absorbing the shock or vibration of 20 impact of the paddles and endless chains with the water to further decrease vibrations in the boat, and tensioning devices are utilized for taking up wear in the chains and 25 insuring the proper tautness of the endless propeller.

In carrying out my invention I enclose the motor and longitudinal motor shaft or 30 drive shaft within a housing extending along the keel line of the boat, and the upper flight of the endless propeller operates in a housing above the motor housing.

The lower flight or working flight of the 35 endless propeller operates below the motor housing and along the keel line beneath the flat bottom of the boat.

The invention consists in certain novel combinations and arrangements of parts as 40 will hereinafter be more fully set forth and claimed. In the accompanying drawings I have illustrated one complete example of the physical embodiment of my invention where in the parts are combined and arranged according to the best mode I have thus far 45 devised for the practical application of the principles of my invention.

Figure 1 is a view in side elevation of a 50 pleasure boat equipped with the propulsion mechanism of my invention.

Figure 2 is a vertical longitudinal sec-

tional view along the keel line of the boat, as at line 2-2 of Figure 3.

Figure 3 is a plan view showing the cockpit and fore and aft arrangement of the seats, the propeller mechanism being indicated by dotted lines.

Figure 4 is an enlarged transverse sectional view of the boat, amidships, as at line 4-4 of Figure 3.

Figure 5 is an enlarged detail view partly in section, showing an end of one of the propellers or paddles, the chain, and one of the four guide rails, and rollers, for the chains.

Figure 6 is a fragmentary view, looking from the right in Figure 5, and partly broken away.

Figure 7 is a detail perspective view of one of the outboard guide-links of the endless chains.

Figure 8 is a detail, vertical sectional view longitudinally of the boat, at the forward end of the chain drive.

In order that the general arrangement and installation of the propelling equipment may readily be understood I have illustrated a pleasure craft with the usual cockpit 1 and steering apparatus 2, the boat being arranged with a forward passenger compartment 3, with transverse seats 4, and an aft compartment 5 with longitudinal seats 6. The usual windshield 7 and instrument board 8 are illustrated, and the rudder 9 at the stern and deck housing 10 at the bow or stem of the boat are shown. The boat is 85 fashioned with the usual flat bottom 11 and hull 12 constructed in usual manner.

Extending longitudinally of the boat and terminating near the bow and stern, a paddle housing 13 provides an interior way for the forwardly moving, upper flight of the endless propeller, and the housing ends in a curved, forward shield 14 and complementary curved shield 15 at the stern of the boat, the fore and aft ends of the housing opening through the bottom of the boat to the water. The housing is provided with upright side walls 16, and doors or removable plates or boards are provided for the housing to permit access to its interior when 100

necessary, the housing of course being watertight and sealed against leakage.

The horizontally extending flat bottom 17 of the paddle housing forms a dividing partition between the paddle housing and a motor housing 18 in which the motor 19 is installed, the motor housing being an enclosure beneath the paddle housing and accessible in suitable manner for work on the 10 motor when necessary. The usual control lever C is indicated for controlling the motor. The bottom 20 of the motor housing is flush with the inner wall of the double-bottom of the hull and the motor housing is 15 sealed against leakage of water to its interior.

The longitudinally extending engine shaft or drive shaft 21 projects through a suitable packing in the rear or aft wall of the 20 housing, and power from the motor is transmitted through this drive shaft to the transversely arranged propeller shaft 22 by suitable transmission mechanism indicated by dotted lines at T in Figure 3. The transversely arranged propeller shaft is journaled in bearings 23 secured in the side walls of the paddle housing or of the aft enclosure 15, while an idler or driven, transversely arranged shaft 24, which extends 25 through the forward, shielded enclosure 14, is provided with adjustable bearings, as 25. The bearings 25 are conventional slide blocks, one at each end of the shaft, and they are supported in pairs of grooved 30 plates 26, arranged horizontally upon the vertical walls of the enclosure 14 of the paddle housing. Each bearing 25 has an adjusting or draw bar 27 extending toward the bow of the boat and through a brace 35 board or plate 28 fixed within and extending transversely of the bow of the boat beneath the deck 10. The brace 28 has guide plates 29 thereon for the bars, and each of these bars is provided with a coiled spring 40 45 30 interposed between a washer 31 near the forward end of the bar and one of the brace plates 29. The ends of the draw bars are threaded and an adjusting or lock nut 32 is threaded on the end of each draw bar. 50 By means of the springs a resilient or cushion support is provided for the forward, driven shaft 24, and by means of the adjusting nuts and springs, the endless propeller may be readily adjusted to tighten or loosen 55 it, by sliding the bearings 25.

The propeller shaft 22 and the driven shaft 24 are each provided with a pair of spaced sprocket wheels 33, and over these wheels the endless chains 34 pass, one chain 10 at each side of the keel line of the boat.

On the chains are mounted the transversely arranged paddles or blades 35, and some of the links of the chains are provided with complementary attaching lugs 36 to 15 which the paddles, at their opposite ends, are

bolted or riveted. At each end of the paddles are provided brace links 37, loosely joined at opposite ends to the paddles and chains in order that the links of the chains may readily pass around the sprocket wheels, and the links brace the paddles against the strain of pressure against the water as the boat is propelled. The paddles of course move from fore to aft of the boat under the propelling movement and the brace links 75 hold the paddles against the water pressure.

Some of the links of both chains, as 38 in Figure 7, are provided with guide lugs 39 that are offset from the links and located in vertical planes, and these lugs co-act with two pairs of guide rails 40 extending longitudinally of the boat, one pair to guide the upper flight of the endless chain propeller and the other pair to guide the lower or propelling flight. These guide links also prevent lateral displacement of the chains and of the endless propeller, and they travel or slide through longitudinal grooves 42 in the upper face of the pair of upper rails, and through similar grooves in the lower faces of the pair of 90 lower rails.

Along the upper side of the working or propelling flight of the endless propeller a series of bearing rollers is provided to facilitate the movement of the propelling flight and to reduce friction. For this purpose a series of transversely arranged, and spaced shafts 43 are located between the two lower guide rails 41, and these rails have journal bearings 44 for the opposite ends of the 95 shafts.

Near the journal ends of the shafts are located rollers 45 and between the pair of rollers of each shaft is interposed a spacing sleeve as 46, it being understood that the chains 34 have a sliding contact with the series of rollers, and that the latter turn on their journal bearings with the sliding movement of the chains. In this manner the frictional contact between the moving chains and the rollers is reduced, while the rollers provide the required resistance against the upward pressure of the chains, as well as guide the propelling flight of the endless propeller. 110

Before the links of the chains slide over the roller bearings, after leaving the sprocket wheels 33, the chains encounter a pair of cushions or shock absorbers that are aligned with the two sets of rollers, and these cushions prevent flapping movement of the chains as they pass from their forward sprockets to the roller bearings. These cushions are in the nature of leaf springs 47, pivoted at their forward ends at 48 to suitable supports, and they extend aft a suitable distance beneath the motor housing. The free ends of these leaf springs are resiliently supported at 49 so that any tendency to a 120 flapping or flopping movement of the chains 125 130

as they leave the sprockets is compensated for by the spring devices or resilient supports, and the chains are guided, in frictional sliding contact with the under faces of the 5 leaf springs, to the rollers. Any material slack in the chains is taken up by the chain tighteners, while any slight slackness of the chains is taken up by these leaf springs or cushions.

10 It will be noted that the portion of the chains passing under the cushions is inclined, thus insuring that the blades or paddles, as they enter the water, after leaving the sprocket wheels, are in a feathering position that gradually decreases as to its angularity until the paddle attains its vertical position that is most effective for propulsive purposes. Due to the inclined stretch of the chains, the splash and commotion caused by 15 the paddles entering the water, is materially reduced, and the water is less turbulent to insure a maximum action of the attacking paddles.

The bottom of the boat, forward of the 20 sprockets 33, is also fashioned to insure maximum efficiency of the paddles, by causing a stream of water to flow directly in front of the paddles, and to prevent a vacuum condition, or tendency toward a vacuum 25 condition beneath the prow of the boat. As best seen in Figures 2 and 8, the bottom of the boat is provided with a board 50, or bottom portion that inclines upwardly from the bow or stem of the boat. This inclined 30 bottom portion is approximately the width of the endless propeller, or it may be of greater width, and the aft end of the bottom, forward of the sprockets 33, terminates in a downturned lip 51.

35 As thus described, it will be apparent that the propulsion mechanism of my invention may be driven with smoothness and uniformity, and at high speed, in order that the propelling action may be a continuous one, and that the mechanism is supported and 40 guided with maximum efficiency to prevent slackness of the chains, and to eliminate vibrations to the boat.

Having thus fully described my invention, 45 what I claim as new and desire to secure by Letters Patent is:—

1. The combination with a boat having an endless propeller mechanism operating below the bottom of the boat, of a bottom 50 portion of the boat forward of the mechanism having an inclination upwardly toward the stern of the boat, and a downturned lip at the aft edge of said bottom portion.

55 2. The combination in a boat of the endless chain paddle propeller type, of a housing forming a clearance space for the paddles, a motor housing enclosed by the first housing and forming spaces fore and aft of 60 the motor housing, the bottom portion of

the boat forward of the forward space having an upwardly inclined angle and terminating in a downturned lip in the forward space.

3. In an endless chain propeller, the combination with a pair of drive sprockets and a pair of idle sprockets, a pair of chains, and means for guiding said chains, of a support aft of the forward sprocket, and a pair of cushion devices having resilient 70 mounts on said support and located aft of the forward sprockets.

4. In an endless chain propeller, the combination with a pair of drive sprockets, a pair of idle sprockets having adjustable 80 bearings, and chains on said sprockets, of a support aft of the forward sprocket, a pair of leaf springs pivoted on said support and interposed between the chains and support, and a series of transversely arranged bearing 85 rollers for said chains.

5. The combination with a boat having a paddle housing and an enclosed motor housing extending along the keel line of the boat, 90 said paddle housing having a clearance space for paddles, and fore and aft shields forming spaces at the ends of the motor housing, of a pair of spaced chains having guide links therein, offset guide lugs on said links, paddles mounted on the chains, an upper and 95 a lower pair of spaced rails for said lugs, and a series of transversely arranged bearing rollers journaled in the lower rails as anti-friction bearings for the lower flights 100 of the chains.

In testimony whereof I affix my signature.

EDWARD W. HALL.
